UNITED STATES PATENT OFFICE

JOSEPH GRANAT, OF SAN FRANCISCO, CALIFORNIA

DESIGN FOR A RING SHANK

Application filed April 12, 1932. Serial No. 43,467. Term of patent 7 years.

To all whom it may concern:

Be it known that I, JOSEPH GRANAT, a citizen of the United States of America, residing at San Francisco, county of San Francisco, and State of California, have invented a new, original, and ornamental Design for Ring Shanks, of which the following is a specification, reference being had to the accompanying drawing, forming a part thereof.

The figure is a perspective view of my design both sides of which are the same.

I claim:—

The ornamental design for a ring shank substantially as shown and described.

JOSEPH GRANAT.
